R. D. CONWAY,

TELEPHONE EXCHANGE SYSTEM,
APPLICATION FILED AUG. 24, 1918.

1,383,789.

Patented July 5, 1921.

Inventor:
Roy D. Conway.
by *J. R. Roberts* Atty.

UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,383,789.

Specification of Letters Patent.

Patented July 5, 1921.

Application filed August 24, 1918. Serial No. 251,223.

To all whom it may concern:

Be it known that I, Roy D. Conway, a citizen of the United States, residing at Chatham, in the county of Morris, State of New Jersey, have invented certain new and useful Improvements in Telephone-Exchange Systems, of which the following is a full, clear, concise, and exact description.

This invention relates to telephone exchange systems, and more particularly to such systems in which connections are to be established between telephone lines terminating respectively at manual and automatic exchanges.

15 In some automatic exchange systems, especially those in which toll or long distance connections are established, certain incoming calls are received by an operator who establishes the connection with the desired 20 subscriber's line through the medium of a local trunk circuit extending to the automatic switching apparatus.

In systems of this nature it is desirable to provide means whereby the operator at the 25 manual exchange may signal the operator at the automatic exchange upon the receipt of a call for connection with a line terminating at the automatic exchange and may receive from the automatic exchange characteristic signals indicating the occurrence 30 of the various operations incident to this establishment of such a connection.

The object of this invention is to provide an improved signaling means for a trunk 35 circuit interconnecting exchanges of this character. To attain this object, in accordance with one feature of the invention, a trunk circuit extending between an automatic exchange and a manual exchange is 40 provided with signaling means responsive to subscriber-controlled variations in the resistance of a conductor associated with the local trunk circuit at the automatic exchange leading to the automatic switching 45 apparatus.

In accordance with a second feature of the invention, a busy back circuit is provided at the automatic exchange to simulate the resistance variations of the control conductor, caused by the repeated operations of the switchhook at the automatic subscriber's station, so that when the busy back circuit is associated with the interexchange trunk circuit, characteristic signaling is received at

the manual switchboard to indicate the engaged condition of the called line. 55

In accordance with the third feature of the invention, means is provided whereby the telephone set of the operator at the automatic exchange may be connected with 60 the interexchange trunk before the answer of the called party, but cannot be connected thereto after the called party has answered.

These and other features of the invention, not specifically mentioned above, will more 65 fully appear from the following specification and the annexed drawing, in which Figure 1 shows diagrammatically one embodiment of the invention; Fig. 2 shows 70 schematically certain portions of such embodiment; and Fig. 3 illustrates a modified form of the system shown in Fig. 1.

Referring to Fig. 1 of the accompanying drawing a line A extends to a manual exchange or switchboard X, and is there connected in any well-known manner with a cord circuit B. The cord circuit B may be employed to connect the telephone line A with a trunk circuit C extending from the manual switchboard X to the automatic exchange or switchboard Y, where connection may be made with a local trunk circuit D, for extending the connection to the automatic line circuit E terminating at the switchboard Y. The apparatus shown at 85 the left of the dotted line 2, 2 is located at the manual switchboard X, while that at the right thereof is located at the automatic switchboard Y. The apparatus for connecting the local trunk circuit D with the automatic line E, which is diagrammatically illustrated in the dotted rectangle 1, may be of the type disclosed in Patent No. 1,237,433 granted to Samuel B. Williams, Jr., Aug. 21, 1917. The apparatus shown at the right of 90 the vertical dotted line in Fig. 1 and that shown in Fig. 2 of the Williams patent, with the exception of the automatic line, may be connected with the three-conductor trunk circuit D shown in Fig. 1 of the present application, in which case the slow release relay 14 and the rotary and vertical magnets 11 and 23 would be controlled over the control conductor 3 of the trunk circuit D. A 95 busy back circuit F shown as terminating in a jack 28 at the switchboard Y is adapted for use with the trunk circuit C in case the desired automatic line is engaged. In the

100
105

schematic representation shown in Fig. 2 certain portions of the system illustrated by Fig. 1 are arranged in the conventional form of a Wheatstone bridge. In the modification of the trunk circuit C shown in Fig. 3 the arrangement illustrated is adapted to replace that shown below the dotted line 4, 4 of Fig. 1, correspondingly numbered conductors 29, 30, 31 and 32 of each figure being connected together.

It is thought that the invention will be more fully understood from the following description of the operation of the system illustrated on the accompanying drawing.

With particular reference to the embodiment shown in Figs. 1 and 2, and assuming that a call initiated at the station on the subscriber's line A, in the usual manner, has been answered by the connection of the cord circuit B to the line A, the operator at switchboard X, actuating the listening key 6 to connect her telephone set, not shown, therewith and ascertaining that the connection is desired with line circuit E, terminating at the automatic switchboard Y, inserts plug 7 of cord circuit B, into the jack 8 of an idle trunk circuit C, operating the relays 9 and 10, over a circuit established from battery, through the left-hand winding of relay 10, left-hand normal contact of relay 5, the left-hand normal contact of relay 11, the ring conductor of trunk circuit C, the ring contacts of jack 8 and plug 7, the winding of relay 9, the tip contacts of plug 7 and jack 8, the right-hand normal contact of relay 11, the right-hand normal contact of relay 5, and the right-hand winding of relay 10, to ground. Relay 9, in operating, prevents the lighting of supervisory lamp 12, and relay 10 in operating causes the lighting of lamp 13 over a circuit established from battery, through the normal contact of relay 14, the alternate contact of relay 10 and the lamp 13, to ground. Upon observing the illumination of lamp 13, the operator at switchboard Y actuates the listening and dialing key 15, operating the listening relay 11 over a circuit extending from battery, through the lower alternate contact of key 15, the contact of relay 16, and the winding of relay 11, to ground. Relays 10 and 9 are released thereby, extinguishing lamp 13 and lighting supervisory lamp 12 over a circuit established from battery, through the contact of relay 9, the lamp 12, the sleeve contacts of plug 7 and jack 8, and the resistance 17, to ground. The closure of the alternate contacts of relay 11 connects the operator's telephone set thereat, to the trunk circuit C. Ascertaining that the connection is desired with the automatic line E, the key 15 is retained in an actuated position and the plug 18 is inserted into jack 19 of an idle local trunk D. Relay 20 is operated over a circuit established from the

battery which is connected to conductor 3 at the automatic switching apparatus 1, the contact of relay 21, the sleeve contacts of jack 19 and plug 18, the upper alternate contact of key 15, the lower winding of relay 20, the winding of relay 16, and the contact of the dialing device 22, to ground. The closure of the lower contact of relay 20 short-circuits the series connection of the winding of relay 16 and the lower winding of relay 20. However, relay 20 is locked in an operated condition over a circuit extending from battery, through the lower alternate contact of key 15, and the upper contact and the upper winding of relay 20, to ground. The operator actuates the dialing device 22 in the usual manner to select the called line through the medium of the automatic switching apparatus (see the Williams Patent No. 1,237,433).

After the necessary actuation of the dialing device 22, the key 15 is released which, by the opening of its lower alternate contact, releases relays 20 and 11. Relay 14 is operated over a circuit established from the battery connected to control conductor 3, through the contact of relay 21, the sleeve contacts of jack 19 and plug 18, the normal contact of key 15, the winding of relay 14, and the resistance 23, to ground. Relay 9 is also operated due to the closure of the normal contacts of relay 11, thereby extinguishing supervisory lamp 12. However, lamp 13 does not re-light since the closure of the normal contacts of relay 11 likewise causes the re-operation of relay 10 over the circuit originally traced therefor. Relay 14 in operating completes a Wheatstone bridge, the first arm of which extends from battery, through the contact of relay 14 and resistance 25, while the second arm extends from the battery connected to conductor 3, through the contact of relay 21, the sleeve contacts of jack 19 and plug 18, the normal contact of key 15 and the winding of relay 14, and the third and fourth arms of the bridge include grounded resistances 23 and 24, respectively. The resistances of the various arms of the bridge under the conditions existing at this period during the operation of the system, are so adjusted that the bridge is balanced and therefore no current flows through the winding of relay 5 connected thereacross.

The answer of the called station on the automatic line E causes the operation of relay 21, over a circuit extending from battery, through the right-hand winding of relay 21, the automatic switching apparatus associated with the ring conductor of the local trunk D, the switch-hook contacts of the subscriber's set connected with the line E, the automatic switching apparatus associated with the tip conductor of the local trunk D, and the left-hand winding of re- 130

lay 21, to ground. The operation of relay 21 removes the normal short circuit existing around resistance 36, thereby including such resistance in series with the winding of relay 5, so that the resistance of the second arm of the Wheatstone bridge is materially increased. The consequent unbalancing of the bridge causes a flow of current through the winding of relay 5. Relay 5 in operating 10 opens the circuit traced for relays 9 and 10, to cause the release of relay 9, and the consequent lighting of lamp 12, thereby notifying the operator at switchboard X that the called party has answered. However, lamp 13 does not re-light due to the locking of relay 10 over a circuit extending from battery through the left-hand winding of relay 10, the alternate contact of relay 5, resistance 26, the alternate contact of relay 10 20 and the lamp 13, to ground. The resistance of this circuit is such that lamp 13 does not receive sufficient current to cause its lighting. Relay 20 is marginal in its operation, so that in case the key 15 is actuated after the 25 answer of the called party, relay 20 will not operate over the circuit established from the battery connected to the conductor 3, through the resistance 36, the sleeve contacts of jack 19 and plug 18, the upper alternate 30 contact of key 15, the lower winding of relay 20, the winding of relay 16 and the contact of dialing device 22, to ground. However, relay 16 will operate over this circuit. Therefore, it is impossible to operate relay 35 11 for reconnecting the operator's telephone circuit at switchboard Y to the trunk circuit C after the answer of the called station.

Upon the termination of the conversation, 40 the called party of the substation on the line E, replaces the receiver thereat, causing the release of relay 21 which reestablishes the shunt around resistance 36, thereby again balancing the Wheatstone bridge and consequently releasing relay 5 to open the locking 45 circuit of relay 10 and to reconnect such relay in circuit with relay 9 as originally traced, and causing the operation of the latter mentioned relay, as well as maintaining relay 10 in an operated condition. Lamp 12 is extinguished by the operation of relay 9, thereby furnishing a disconnect signal to the operator at switchboard X who removes 50 plug 7 from jack 8, causing the release of relay 10 to light the lamp 13 over a circuit extending from battery, through the alternate contact of relay 14, the normal contact of relay 10, and lamp 13, to ground. The illumination of lamp 13 serves as a disconnect 55 signal for the operator at switchboard Y and the subsequent removal of plug 18 in response thereto from jack 19 restores all apparatus to normal.

The operation of the system modified in 60 accordance with Fig. 3 agrees with that

described for the system shown in Figs. 1 and 2 until the key 15 is released after the completion of the dialing for selecting the called line. With the modified arrangement, the release of key 15 causes the release of relay 11 and the operation of relay 10 as before, but a circuit is established from the battery connected to the control conductor 3, through the contact of relay 21, the sleeve contacts of jack 19 and plug 18, the 70 normal contact of key 15, the winding of relay 14, and the right-hand winding of relay 27, to ground. As before, relay 14 operates immediately, extinguishing lamp 13 and completing a circuit from battery, 75 through the alternate contact of relay 14, and the left-hand winding of relay 27, to ground. However, relay 27 being differentially wound does not operate under these conditions. Upon the answer of the called 80 station on the automatic line E, relay 21 operates to increase the sleeve resistance of the trunk D, so that the right-hand winding of relay 27 in circuit therewith, receives a decreased amount of current, thereby operating relay 27 which, as in the case of relay 5, disconnects relay 10 from the trunk circuit C, to cause the release of supervisory relay 9 and the consequent lighting of supervisory lamp 12 as previously described. As before 90 relay 10 is locked over a circuit extending from battery, through the left-hand winding of relay 10, the alternate contact of relay 27, resistance 26, the alternate contact of relay 10 and the lamp 13 to ground. Lamp 13 receives insufficient current over 95 this circuit to cause its lighting. Upon the termination of the conversation at the station on the automatic line E, the relay 21 releases and short-circuits the resistance 36 100 as in the previous case, thereby decreasing the resistance in series with the right-hand winding of relay 27, causing the release of such relay. Relay 9 operates, relay 10 is maintained in an operated condition and 105 the lamp 12 is extinguished as previously described in connection with the release of relay 5. Upon the removal of plug 7 from jack 8, relay 10 is released and lamp 13 is 110 lighted as previously described, and the subsequent removal of plug 18 from jack 19 causes all apparatus to return to normal, 115 as before.

The busy back circuit F shown in Fig. 1 is 120 adapted for use either with the arrangement shown in Fig. 1 or as modified by Fig. 3, in case the desired automatic line is engaged. If the operator at the automatic switchboard Y finds that the line E is engaged, the plug 18 is inserted into jack 28, 125 thereby operating relay 33 over circuit extending from battery, through the operating and non-inductive windings of relay 33 in series, the sleeve contacts of jack 28 and plug 18, where it joins the sleeve cir- 130

1. cuits traced for trunk circuit C in connection with the description of the operation of the system shown in Figs. 1 and 3. The combined resistance of the non-inductive 5 and operating windings of relay 33 agrees with that of the apparatus connected to the sleeve contact of jack 19, upon the answer of the called station on the automatic line E, and causes changes in the apparatus of 10 the system similar to that resulting from the answer of the called party, including the lighting of supervisory lamp 12. The closure of the contact of relay 33 establishes a circuit from battery, through the contact 15 of relay 33, the winding of relay 34 and interrupter 35, to ground. Relay 34 is operated and released in accordance with the interruptions produced by the interrupter 35. Upon each operation of relay 34 the 20 non-inductive winding of relay 33 is short-circuited, thereby reducing the resistance in circuit with the sleeve contact of plug 18 sufficiently to agree with that in circuit therewith when plug 18 is inserted into 25 jack 19 prior to the answer of the called station. The responsive apparatus is therefore restored to the conditions existing immediately following the insertion of plug 18 into jack 28, and lamp 12 is extinguished. 30 In this way lamp 12 is flashed in a characteristic manner under control of the constantly operating interrupter 35, to notify the operator at switchboard X regarding the engaged condition of the automatic line E. 35 However, due to the fact that relay 10 is maintained in an operated condition, lamp 13 remains extinguished until plug 7 is removed from jack 8 in response to the flashing of lamp 12.

40 It will be noted from the above description that signaling control means is provided for the trunk circuit, in either case, responsive to the variations produced in the control conductor, associated with the automatic exchange to produce suitable signals at the manual exchange.

What is claimed is:

1. A telephone exchange system comprising a trunk circuit extending from a first to 50 a second central office, a line circuit terminating at the second central office, a station thereon, a control conductor, switching means at the second central office controlled over the conductor and adapted to connect 55 the trunk to the line, means responsive to the answer of the called station to cause a predetermined variation in the resistance of the conductor, a relay in the trunk circuit operating upon the connection of the trunk 60 with the line and releasing upon the response of the called station, and a signaling device at the first central office controlled by the relay.

2. A telephone exchange system comprising 65 a trunk circuit extending from a first to

a second central office, a telephone line terminating at the second central office, a station thereon, means to connect the trunk with the line, an operator's telephone set at the second central office, switching means 70 for connecting the telephone set with the trunk circuit prior to the response of the station on the connected line, and additional means controlled by the response of the station to prevent the connection of the telephone circuit to the trunk circuit during the continued connection of the trunk with the line.

3. A telephone exchange system comprising a trunk circuit extending from a first to 80 a second central office, a line terminating at the second central office, a station thereon, switching means for connecting the trunk with the line, an operator's telephone set at the second central office, operator-controlled 85 switching means for connecting the operator's telephone set to the trunk circuit prior to the response of the station, and additional means associated with the first-mentioned 90 switching means for preventing the connection of the operator's telephone set to the trunk after the response of the station.

4. A telephone exchange system comprising a trunk circuit extending from a first to 95 a second central office, a Wheatstone bridge associated with the trunk circuit, a control circuit at the second office for connection with the trunk circuit to cause repeated predetermined variations in the resistance of one arm of the bridge, and means responsive 100 to such variations for producing characteristic signals at the first office.

5. A telephone exchange system comprising a trunk circuit extending from a first to 105 a second central office, a signaling device at the first central office, an operator's telephone set at the second central office, means at the second central office for connecting a telephone set with the trunk circuit, a line terminating at the second central office, a station thereon, a control conductor, switching means at the second central office controlled 110 over the conductor and adapted to connect the trunk to the line, subscriber-controlled means responsive to the answer of the called 115 station to cause a predetermined variation in the resistance of the conductor, additional switching means at the second central office responsive to such variations for controlling the signaling device and for rendering the 120 first-mentioned means ineffective.

6. A telephone exchange system comprising a trunk circuit extending from a first to a second central office, a line terminating at the second central office, a station thereon, switching means for connecting the trunk to the line to call the station, a signaling device at the first central office, a Wheatstone bridge associated with the trunk circuit, a relay associated with the 125 130

switching means, conductors between the contacts of said relay and the arms of the bridge, said bridge being unbalanced by the actuation of said relay upon the response of 5 the called station, and a relay responsive to the unbalance of the bridge to control the signaling device.

7. A telephone exchange system comprising a trunk circuit extending from a first to 10 a second central office, a control circuit at the second central office, switching means for connecting the trunk with the control cir-

cuit, a Wheatstone bridge associated with the trunk circuit, a relay in the control circuit, conductors between the contacts of said relay and the arms of the bridge, said bridge being unbalanced by the actuation of said relay, and means controlled by the bridge to produce a characteristic signal at the first central office. 15

In witness whereof, I hereunto subscribe my name this 19th day of August A.D., 1918. 20

ROY D. CONWAY.
